United States Patent Office

Des. 197,980
Patented Apr. 14, 1964

197,980

BUTTER DISH OR SIMILAR ARTICLE

Thomas E. Brown, Woonsocket, R.I., assignor to Rexall Drug and Chemical Company, Los Angeles, Calif., a corporation of Delaware

Filed Oct. 10, 1963, Ser. No. 76,939

Term of patent 14 years

(Cl. D44—5)

FIG. 1

FIG. 2

FIG. 4

FIG. 3

FIG. 5

FIG. 8

FIG. 9

FIG. 6

FIG. 7

FIGURE 1 is a side elevation view of a butter dish showing my new design;

FIGURE 2 is a top plan view thereof;

FIGURE 3 is an end elevation view thereof;

FIGURE 4 is a side elevation view of the butter dish showing my new design, with the top separated from the base of the container;

FIGURE 5 is an end elevation view thereof;

FIGURE 6 is a top plan view of the base of the container;

FIGURE 7 is a fragmentary bottom plan view thereof;

FIGURE 8 is a cross section taken on line 8-8 of FIGURE 3; and,

FIGURE 9 is a cross section taken on line 9-9 of FIGURE 1.

I claim:

The ornamental design for a butter dish or similar article as shown.

References Cited in the file of this patent

UNITED STATES PATENTS

D. 166,619 Paul ----- Apr. 29, 1952